PAGE 3

Fig. 1 is a perspective view taken from the front and to the left side of a combined trailer, wire stringer and tensioner, embodying our new design;

Fig. 2 is a side elevation of the left side of Fig. 1.

Fig. 3 is a side elevation of the right side of Fig. 1.

Fig. 4 is a plan view of the trailer type wire stringer and tensioner as seen from above in Fig. 3.

We claim:

The ornamental design for a combined trailer, wire stringer and tensioner, as shown.
